UNITED STATES PATENT OFFICE

2,545,611

CASE FOR ELONGATED ARTICLES

Roy L. Flannery, Chicago, Ill., assignor to The
Boye Needle Company, Chicago, Ill., a corpora-
tion of Illinois

Application January 21, 1949, Serial No. 71,832

2 Claims. (Cl. 150—34)

1

This invention relates to a case for elongated articles such as crochet hooks, knitting pins, and the like.

Articles such as crochet hooks, knitting pins, yarn bobbins, stitchholders, and other elongated objects of this character are difficult to package in kits or cases because of the tendency of the articles to become misaligned or crossed in the cases. To obtain alignment, it is now the practice to provide pockets in cases which extend across a large portion of the case and receive at least one-half of the crochet hook or pin. Even in this structure, there is a tendency for the article to extend angularly from the pocket and to cross articles from other pockets. Further, the pockets conceal a substantial portion of the article so that the user cannot see the ends thereof.

An object of the present invention is to provide a case in which articles such as crochet hooks and knitting pins, yarn bobbins, stitchholders and like elongated objects will be supported in such a manner as to maintain them throughout their lengths in spaced, parallel arrangement while at the same time exposing the ends of each article to view. Yet another object is to provide a case structure in which such elongated articles will be supported about their centers and with their ends extending freely therefrom, the case being constructed so as to maintain the protruding ends in parallel, spaced arrangement. Yet another object is to provide a case in which parallel sheets are sealed together about their edges so as to trap air therein whereby in the locking of crochet hooks or knitting pins by means of loops in the center of the case, a pressure is exerted against such articles to hold them in spaced, parallel arrangement throughout their lengths, irrespective of the angle in which the case is supported. Other specific objects and advantages will appear as the specification proceeds.

The invention is illustrated in specific embodiments by the accompanying drawings, in which—

Fig. 1 is a perspective view of an open case embodying my invention; Fig. 2, a perspective view of the case in folded condition; Fig. 3, an enlarged detail sectional view, the section being taken as indicated at line 3 of Fig. 1; Fig. 4, a transverse sectional view, the section being taken as indicated at line 4 of Fig. 1; Fig. 5, a perspective view of a modified form of case embodying my invention, the case being shown in open condition; Fig. 6, a view similar to Fig. 5 but showing the case in closed condition; Fig. 7, a transverse sectional view, the section being taken as indi-

2

cated at line 7 of Fig. 6; Fig. 8, a perspective view of another modified form of case holding various elongated objects the case being shown in open condition; Fig. 9, a perspective view of the case closed; and Fig. 10, a transverse sectional view, the section being taken, as indicated, at line 10—10 of Fig. 8.

In the illustration given in Figs. 1 to 4 inclusive, 10 designates a case body which is formed by bringing together thermoplastic sheets 11 and 12 and heat sealing the same at their edges, as indicated at 13 in Fig. 3. In heat sealing the edge portions, a small amount of air is trapped within the space 14, as shown best in Fig. 3. The outermost sheet 11 is preferably provided at one end with a flap extension 15 provided with a fastener button 16 adapted to engage a ball fastener secured to the other end of the strip or sheet 11.

10 To the inner sheet 12 is secured a relatively narrow strip 17 which is heat sealed to the sheet 12 not only at its ends but at spaced points indicated by the numeral 18 in Fig. 3, thus providing loops 19 adapted to receive the central portions

15 of articles to be held within the case. In the specific illustration given in Fig. 1, crochet hooks 20 are secured within the loops 19, both ends of the hooks being exposed. In a similar manner, knitting pins may be secured within the loops 19 and the ends thereof exposed on both sides of the strip 17.

20 To protect the ends of the articles, I prefer to employ flexible side flaps 21, as shown more clearly in Figs. 1 and 4. The side flaps 21 are 35 preferably formed of transparent plastic material and are heat sealed to the upper sheet 12 along the side edges thereof, as indicated at 22 in Fig. 4.

While I prefer to form the case of thermoplastic material as illustrated, and to secure the parts together by heat sealing, it will be understood that other material may be used.

30 In the operation of the case shown in Figs. 1 to 4 inclusive, the crochet hooks or knitting pins are extended through the loops 19 so that 40 the ends thereof extend under the flaps 21 along the sides of the case. I have found that the trapped air within the chamber 14 even though this may be relatively small in amount, serves to resist the downward flexing of the upper wall 50 12 when it is engaged by the body of the crochet hook or knitting pin and tends to form a rounded channel or trough-like bed receiving the article throughout its length and causing the article to lie firmly in a parallel position with respect to the adjacent articles. There is thus no tend-

ency for the article to occupy an angular position crossing an adjacent article at one end. Even after considerable use in which the articles are repeatedly removed and replaced within the case, the air-supported top web 12 remains effective in exerting pressure against the articles to maintain them in a parallel alignment. This result is accomplished even though the strip 19 is relatively narrow, in order to expose fully the end portions of the article.

In removing the crochet hook from the structure shown in Fig. 1, the flap over the hook portion of the article is turned back and a particular crochet hook selected according to the desired size. The selected hook is drawn away from the loop and after being used is returned by inserting the end opposite the hook end through the loop. As the hook is returned into position, the upper wall 12 of the case flexes downwardly below the particular loop in which the crochet hook is inserted while forming a slight ridge on either side of the hook tending to hold it in true alignment with the loop through the length of the article.

In the modification shown in Figs. 5, 6 and 7, a case 23 formed of an inner sheet 24 and an outer sheet 25 is produced in very much the same way as described in connection with the structure of Figs. 1 to 4 inclusive. Between the sheets which are sealed together at their edges is a space containing air and indicated by the numeral 26. The case is folded along a median line 27 and the outer sheet 25 is extended along its ends to one side of said median line 27 to form the end flaps 28. The end flaps 28 are provided with fasteners consisting of the spring socket members 29 and the ball fasteners 30, as shown best in Fig. 6. The inner wall 24 is provided with a narrow strip 31, heat sealed in spaced relation to form the loops 32.

In the operation of the structure shown in Figs. 5 to 7 inclusive, articles such as crochet hooks, knitting pins, etc. are inserted through the loops 32 and the case is folded along the median line 27 into the form shown in Fig. 6, the end flaps 28 are then turned inwardly and secured, as shown best in Figs. 6 and 7. In other respects, the operation is the same as described in connection with the modification of Figs. 1 to 4 inclusive. The air cushion supporting the inner wall 24 is effective in providing a slight trough about each of the articles so as to maintain them firmly in parallel relation, irrespective of the positioning or handling of the case.

In the modification shown in Figs. 8 to 10 inclusive, the case structure shown is very similar to that illustrated in Figs. 1 to 4. However, instead of having one central strip forming loops extending along the center of the case, I provide

along one-half of the case 47 the spaced strips 33 and 34. The strip 33 is preferably heat sealed to provide a large loop 35 adapted to receive a pin supporting card 36. The loop 33 is also provided with loops 37 and 38 which receive the stitchholder 39.

The strip 34 is heat sealed at intervals to the inner wall 12a of the case to provide loops 40, each receiving a group of yarn bobbins 41.

10 The outside of the case shown in Figs. 8 to 10 inclusive, is provided with a central strip 42 heat sealed or otherwise secured to the inner wall 12a of the case at spaced intervals to provide the loops 43 and 44. The loops 43 receive knitting pins 45 and the loop 44 receives a crochet hook 46.

While in the foregoing specification, I have set forth specific structures in considerable detail for the purpose of illustrating embodiments of the invention, it will be understood that such details of structure may be varied widely by those skilled in the art without departing from the spirit of my invention.

I claim:

1. In a case for enclosing elongated articles, a pair of thermoplastic sheets heat sealed to each other about their edges to provide an air cushion therebetween, said united sheets forming a case body adapted to be folded upon itself along a median line, a strip extending along the innermost of said sheets and heat sealed thereto at spaced intervals to form retaining loops for said elongated articles, said air cushion forming grooves receiving said elongated articles therein and maintaining them in parallel relation, and means for locking said case in folded relation.

2. In a case for enclosing elongated articles, a pair of flexible plastic sheets sealed together about their edges to provide an air cushion therebetween, said united sheets forming a case body adapted to be folded upon itself along a median line, a strip extending along the innermost of said sheets and sealed thereto at spaced intervals to form retaining loops adapted to receive said elongated articles, the air pressure in the space between said sheets forming ridges about said elongated articles confined within said loops to maintain said articles in parallel relation, and locking means for securing said case in folded relation.

ROY L. FLANNERY.
